UNITED STATES PATENT OFFICE.

WILLIAM JACKSON LUND AND LUCIEN PAUL MELLERIO, OF LEICESTER, ENGLAND,
ASSIGNORS, BY MESNE ASSIGNMENTS, TO THE CELASTIC CORPORATION, OF WIL-
MINGTON, DELAWARE, A CORPORATION OF DELAWARE.

SHOE STIFFENER AND METHOD OF INCORPORATING IT IN SHOES.

Application filed October 7, 1927, Serial No. 224,702, and in Great Britain October 30, 1926.

This invention relates to stiffening parts of boots and shoes, and is herein illustrated as embodied in a toe stiffener and a method of incorporating it in a boot or shoe.

5 In the manufacture of boots and shoes, box toe blanks have been used containing stiffening substances such as celluloid which may be softened or gelatinized by treatment with a solvent preparatory to the pulling-over or 10 lasting operation and subsequently become stiff and resilient when the solvent has evaporated. These substances have been used in various ways in connection with fabric bases, for example, as a coating for the fabric or as 15 an impregnating material for the fabric.

In one aspect the present invention relates to a stiffener blank the stiffening substance of which is made up in whole or in part of fibres composed of a gelatinizable substance. For 20 example, the stiffener blank may be made of the product known in the artificial silk trade as celanese, the fibres or threads of which are composed of cellulose acetate. By the em- 25 ployment of a fabric such as this the fibres of which may be gelatinized by treatment with a suitable solvent such as acetone, several ad- 30 vantages are secured. A substantial uniformity of distribution of the stiffening substance throughout the part to be stiffened is assured. An extremely thin blank may be used since the blank is made entirely of gelatinizable material. The stiffener blank, besides being thin, is flexible and may be incorporated, for 35 example, in a turned shoe and treated, when the shoe is on the first last just prior to being turned, by applying to the toe portion of the lining of the shoe a sponge wet with solvent so as to soften and gelatinize the blank preparatory to turning the shoe right 40 side out and conforming it to the second last.

In another aspect the invention comprises a method of providing a stiffener containing fibres of gelatinizable material, treating the fibres to gelatinize them and conforming the stiffener to a last. The method may be practised in the manufacture of a turned shoe after the particular manner which has been described above, or in the manufacture of 45 turned or other shoes in the usual manner.

50 Referring to the accompanying drawings, Fig. 1 is a plan of a toe stiffener blank, in which the present invention is embodied, and Fig. 2 is a cross-section on the line 2—2 of Fig. 1.

The blank shown in the figures is made of 55 fibres or threads of cellulose acetate. In order to gelatinize the cellulose acetate it may be treated with a suitable solvent such, for example, as acetone. This treatment may take place before or after the blank has been 60 incorporated in the upper of the shoe and will preferably be carried out prior to the turning of a turned shoe and prior to the pulling-over operation on other shoes. The immediate effect of the solvent is to convert 65 the cellulose acetate threads into a sticky gelatinous condition so that after the toe portion of the shoe has been conformed to the last and the solvent has evaporated, the cel- 70 lulose acetate is left in the form of a thin, 75 spring film firmly attached to the parts of the upper between which it lies.

Although the fabric of the illustrated stiffener is composed of woven cellulose acetate threads, it is obvious that other materials 75 than cellulose acetate and other arrangements of threads or fibres may be employed. The fabric may be produced in a variety of ways. It may be a felted product composed of 80 fibres of gelatinizable material mixed with felting fibres or bonded by a suitable adhesive. For example, the gelatinizable fi- 85 brous material may be celluloid and the felting fibres wool, or the fibres of celluloid may be bonded together by collodion. Again, the fabric may be made by knitting or weav- 90 ing and may comprise strands of yarn or thread, such as cotton, which are not gelati- 95 nizable, so that the stiffener, when softened, shall not entirely lose its structure and pass temporarily into a mere layer of soft gelatinous material. In many instances, however, it is desirable that substantially all of the fi- 100 brous content of the fabric be gelatinizable, since it then becomes readily possible, after the stiffener has been conformed to the last and while it is still soft, to change the thickness of the stiffening material at a selected locality. For example, it is possible by proper pressing and rubbing over the rear margin of a toe stiffener to force the softened material more or less into the lining and to thin the rear margin of the stiffener after the manner desired in plain vamp shoes.

The material, whether composed in whole 105 or in part of the gelatinizable fibres, may be used, if desired, in a plurality of superposed layers of like or different character and of

different area so as to produce in the composite stiffener blank a margin of decreasing thickness. For example, two layers of woven fabric may be used, or a small layer of coarsely knitted fabric with a backing of thin woven fabric of full size. Or, in order to produce a similar result, namely a thinned margin, a stiffener blank made of a single layer of woven fabric may have its rear margin frayed for 10 a distance from its edge in such manner as gradually to reduce the content of gelatinizable fibre as the edge is approached.

As an example of another way in which the blanks may be prepared, a fabric of suitable texture, woven, knitted, felted or otherwise made, may be acetylated or nitrated to a suitable degree in the web and while still wet cut up into properly shaped blanks, and the still wet blanks sized or otherwise treated 20 superficially in a bath of a solution of a sizing agent, preferably soluble in the intended gelatinizing solvent or in a bath of a solvent such as alcohol which will superficially gelatinize the fibres. The blanks will not be stiffened to any appreciable extent by such treatments but at the same time will be freed from any tendency when dry to produce fluff or dust when handled.

Having described our invention, what we 30 claim as new and desire to secure by Letters Patent of the United States is:

1. A shoe stiffener blank containing a gelatinizable stiffening substance in fibrous form.

2. A shoe stiffener blank containing an ester of cellulose in fibrous form. 35

3. A shoe stiffener blank comprising a fabric some of the fibres of which are gelatinizable.

4. A shoe stiffener blank made of a cellulose ester fabric. 40

5. The method of making a stiffener blank which comprises cutting the blank from a fabric containing fibres of a gelatinizable substance and treating the blank to counteract any tendency of the cut fibres to give off fluff 45 or dust when handled.

6. The method of stiffening portions of the uppers of shoes which comprises incorporating in the upper of a shoe a blank containing a gelatinizable stiffening substance 50 in fibrous form, treating the blank with a solvent for the stiffening substance to gelatinize it, and conforming the blank with the upper to the last.

7. The method of stiffening portions of the 55 uppers of shoes which comprises incorporating in the upper of a turned shoe a blank containing a gelatinizable stiffening substance in fibrous form, treating the blank with a solvent while the shoe is wrong side out, turning the shoe right side out, and conforming the blank with the upper to the second last.

In testimony whereof we have signed our names to this specification.

WILLIAM JACKSON LUND.
LUCIEN PAUL MELLERIO.
